BOTTLE CRATE

Fred H. Mahler, St. Paul, Minn., assignor to John Wood Manufacturing Company, Inc., Conshohocken, Pa., a corporation of Delaware

Application February 18, 1938, Serial No. 191,252

9 Claims. (Cl. 217—19)

It is an object of this invention to provide a bottle crate having walls constructed from a novel combination of wood and metal slats imparting unusual strength and durability while reducing the cost and weight of the structure.

Another object is to so combine wood slats with metal slats in the walls of a crate as to permit expansion and contraction of the wood members while retaining the metal members under lateral compression between wood members and thereby deaden or muffle the noise which is ordinarily produced in the use of all-metal structures of this kind.

A further object is to provide in a crate of the class described, sheet metal wall members which are rendered adequately stiff by a novel arrangement of marginal flanges.

Other objects will appear and be more fully pointed out in the following specification and claims.

Referring to the accompanying drawings:

Figure 1 is a plan view of my improved crate; Fig. 2 is a vertical section taken on the line 2—2 of Fig. 1;

Fig. 3 is a section taken on the line 3—3 of Fig. 1;

Figs. 4, 5 and 6 are fragmentary horizontal sections taken on the lines 4—4, 5—5 and 6—6 of Fig. 2;

Fig. 7 is an enlarged vertical section taken on the line 7—7 of Fig. 1, and

Fig. 8 is a perspective view of one of the corner joints between wood slats.

My improved crate has vertical side and end walls connected together at the corners as hereinafter described. Each of the side walls is composed of three wood slats indicated by the numerals 7, 8 and 9 respectively and metal slats 10 and 11 interposed respectively between the slats 7 and 8, and 8 and 9. Each of the end walls is composed of horizontally extending metal slats 12 confined between wood slats 13 and 14 and a third wood slat 15 disposed above the slat 13 and formed with a handle opening 16.

The several metal slats 10, 11 and 12 are similarly formed from sheet metal and each has a plane vertical main panel extending approximately in the vertical plane of the outer surface of the wood slats of the same wall and integral flanges 17 extending along the upper and lower edges of the main panel and projecting inwardly therefrom. These flanges 17 project obliquely toward the adjoining wood slats and are of double thickness of metal, having integral flanges 18 extending outwardly from their

inner edges to abut against the wood slats respectively.

An angle bar 19 extends vertically at each corner of the crate and is preferably formed with inwardly bent flanges 20 engaging the several slats of the adjoining walls in vertical grooves formed in the slats. As best shown in Figs. 4 to 8 inclusive, the several wood slats have mitered end portions 21 which interlock, one with another, at each corner and are perforated vertically to receive a vertical tie rod 22 at each corner. The metal slats 10 and 11 have perforations in their flanges 17 and 18 near each corner to receive the rods 22 and the flanges of the metal slats 12 are similarly perforated to receive the rods 22. As best shown in Fig. 7, the end portions of the flanges 17 and 18 of the slats 12 overlap the corresponding flanges of the slats 11. To retain the several flanges 17 and 18 of the metal slats under compression, rivets 23 fasten the angle bars 19 to the wood slats bordering the upper and lower edges of the crate. A bottom for the crate is formed by a multiplicity of spaced, parallel rods 24 having their ends secured in the end walls of the crate. These rods are braced and connected together by a transversely extending channel bar 25. A suitable partition structure for separating the bottles in the crate comprises an upper grid consisting of a multiplicity of crossed rods 26 and 27 and a lower grid structure comprising crossed rods 28 and 29. These upper and lower grid structures are connected together by posts 30 which are perforated to receive the several rods 26, 27, 28 and 29 at their several intersections.

My improved crate is particularly, although not exclusively, adapted for use in transporting milk bottles. Crates of this class are so frequently washed that the wooden members absorb considerable moisture and must be free to expand and contract. Ordinarily, wood crates have the disadvantage of becoming progressively heavier while in use, due to the absorption of moisture and my improved crate minimizes this disadvantage by reducing the amount of wood embodied in the crate by about 40%. As my metal slats are otherwise considerably lighter than wood slats of equal strength, my crate is considerably lighter than the ordinary reinforced wood crates. All-metal crates are objectionable because of the noise and rattling incident to their use, but this objection does not apply to my invention because I maintain the metal slats under compression between the wooden slats so that vibration and free movement of the metal

parts is prevented. The longitudinal flanges 17 and 18 on the metal slats are sufficiently resilient to maintain the contact with the wood members and to compensate for the expansion and contraction of such members at all times. It will also be evident that the flanges along the edges of the metal slats are formed by a double thickness of metal so that these flanges greatly strengthen the crate and impart ample longitudinal rigidity to each slat. This makes it practical to construct the metal slats from relatively light gauge sheet metal and substantially reduces the cost of the crate.

Having described my invention, what I claim as new and desire to protect by Letters Patent is:

1. A bottle crate comprising, a plurality of walls selected walls being formed from alternate wooden and metal slats and means securing the slats of said walls together at the corners of the crate, each of said metal slats being formed with a main panel and flanges extending along the longitudinal edges of said panel in engagement with the edges of the wooden slats.

2. A bottle crate comprising, a plurality of walls each formed from alternate wooden and metal slats secured together at the corners of the crate and each of said metal slats being formed with a main panel extending in a common plane with the outer faces of the adjacent wooden slats and integral flanges extending along the longitudinal edges of said panel and resiliently engaging the adjacent wooden slats.

3. A bottle crate having in combination a plurality of walls each formed from alternate wooden and metal slats, the several metal slats being channel shaped in vertical cross section and having flanges along their edges projecting obliquely into engagement with the adjacent wooden slats, said flanges being sufficiently resilient to maintain contact with the wooden slats during the expansion and contraction of said slats.

4. A bottle crate comprising walls having top and bottom wooden slats and intermediate sheet metal slats confined between pairs of said wooden slats, means for securing the slats of each wall together at the corners of the crate and flanges extending along the longitudinal edges of said metal slats in resilient engagement with the edges of the adjacent wooden slats, the flanges of each slat being arranged to be sprung toward each other upon the swelling of the abutting wooden slats.

5. A bottle crate having side and end walls joined together at the corners of the crate, each of said walls having top and bottom wood slats and intermediate slats formed from sheet metal, the several metal slats being confined between wood slats, each of said metal slats being formed

with resilient flanges extending along its upper and lower edges in engagement with the edges of the adjacent wood slats and each of said flanges comprising a double fold of sheet metal.

5 6. A bottle crate having plane side and end walls joined together at the corners of the crate, each of said walls having top and bottom wooden slats and intermediate slats formed from sheet metal and confined between the adjacent wooden slats, each of said metal slats comprising a main, vertical panel extending substantially in the plane of the outer surface of the wooden slats of the same wall and flanges extending along the longitudinal edges of said main panel in engagement with the edges of the adjacent wooden slats, each of said flanges comprising a double fold of sheet metal.

7. A bottle crate having in combination a plurality of walls, selected walls being formed of alternate wooden and metal slats, means for securing the slats of each wall together at the corners of the crate and resilient flanges extending along the longitudinal edges of a metal slat in engagement with the edges of adjacent wooden slats whereby the metal slat is maintained under compression between adjacent wooden slats to prevent free movement of the metal slat, the said flanges being sufficiently resilient to maintain contact with the wooden slats during expansion and contraction of the wooden slats.

8. A polygonal bottle crate comprising, alternate wooden and metal slats substantially horizontally disposed and forming selected walls of the crate, each of said metal slats being formed with a main panel and resilient flanges extending along the longitudinal edges of said panel in engagement with the adjacent edges of the wooden slats, and means securing the slats of said walls together at the corners of the crate, said means including a vertically disposed tie rod secured to adjacent ends of said wooden slats and passing through adjacent ends of the flanges of said metal slats.

9. A polygonal bottle crate comprising, alternate wooden and metal slats substantially horizontally disposed and forming selected walls of the crate, adjacent ends of said wooden slats overlapping at the corners of the crate, each of said metal slats being formed with a main panel and resilient flanges extending along the longitudinal edges of said panel in engagement with the adjacent edges of the wooden slats, and means securing the slats of said walls together at the corners of the crate, said means including a vertically disposed tie rod passing through the overlapped ends of the wooden slats and through the flanges of the metal slats.
